WOVEN WIRE FABRICS

Ferdinand Steinhart, Kearny, N. J., assignor to
The Lindsay Wire Weaving Company, Cleve-
land, Ohio, a corporation of Ohio

Application August 22, 1936, Serial No. 97,353
In Great Britain August 28, 1935

11 Claims. (Cl. 245—10)

This invention relates to woven wire fabrics and more particularly to a means for uniting together sections of such fabric so as to provide endless wire cloths for Fourdrinier paper making machines. The present invention has particular reference to wire fabrics woven with a twill weave. In a twill weave each weft wire passes alternately under two warp wires and over one warp wire, the intersection of weft with 5 warp wires being advanced by one warp wire at each successive pick.

The invention contemplates preparing the ends of the twill weave woven wire so they may readily be united by welding, brazing or soldering. 15 The first step comprises removing a plurality of the weft wires from the ends of the fabric to be joined. The loose wire ends are then opened out so that every third warp wire end is bent downwardly and every pair of intervening warp wire 20 ends is bent upwardly. The loose warp wire ends are then severed or trimmed shortly beyond where they cross the last remaining weft wire. This results in every third warp wire terminating in a downwardly sloping end portion and in 25 every pair of intervening warp wires terminating in upwardly sloping end portions. The ends of the fabric so prepared are then abutted with the warp wires of the two sections of fabric in substantially coplanar relationship and the projecting warp wire ends of one section united to those of the other section by welding, brazing or 30 soldering in a known manner. The two ends of the fabric may be united so that the twill weave is continuous across the seam or, if desired, the 35 ends may be so abutted that the twill weave is interrupted at the seam.

The welded joint produced by the improved method is strong and durable and will invariably outlast the fabric. It does not protrude appreciably beyond either face of the fabric and the meshes at the joint are of substantially the same size as the meshes throughout the fabric. The seam or joint, therefore, will not mark the paper nor interfere with the drainage qualities of the 45 fabric.

Further objects and advantages will become apparent as this specification proceeds. Referring to the drawings forming a part thereof:

50 Figs. 1 to 5 are longitudinal sectional views illustrating the various stages in the preparation of the ends of the fabric;

Fig. 6 is a longitudinal sectional view showing the two fabric ends assembled together ready for 55 welding;

Figs. 7, 8 and 9 illustrate how the different warp wires are abutted together; and

Fig. 10 is a view similar to Fig. 6 showing the position of the fabric ends prior to welding a seam in which the twill weave is continuous across the 5 seam.

Referring again to the drawings, the weft wires are indicated by the reference characters *a*, *b*, *c*, *d*, *e*, *f* and the warp wires are designated *1*, *2* and *3*.

In the preferred manner of carrying out the invention the first step in the process of preparing the ends of the fabric consists in withdrawing the three end weft wires *a*, *b* and *c*. These wires are drawn out through the side edges of 15 the fabric preferably by pulling on one end of the weft wires in line with the axis thereof. The weft wire *c* may be raised slightly while withdrawing it so as to assist it in riding over the crest of warp wire *1* and the crests of the 20 corresponding warp wires. The weft wire *d* is then removed by drawing it obliquely to the plane of the fabric while withdrawing it through the end edge of the fabric, so as to progressively raise the end of every third warp wire. At this 25 stage in the process of preparing the ends of the fabric the warp wire would assume approximately the position indicated in Fig. 2.

After the end of warp wire *3* and every third similar warp wire throughout the width of the 30 fabric has been lifted as heretofore described, the ends of the other warp wires *1* and *2* are opened apart so as to assume approximately the position illustrated in Fig. 3. This operation is performed by inserting a needle or other suitable tool between the ends of the pairs of wires 35 *2* and *3* throughout the width of the fabric. Either during this operation or subsequently thereto every third warp wire *1* is further separated at its end from the ends of the warp wires *40* *2* and *3* by further raising the ends of the warp wires *2* and *3*, as in Fig. 4, and pressing the warp wires close up against the weft wire *c* where the wire *1* crosses the wires *2* and *3*.

The ends of the warp wires *1*, *2* and *3* are now 45 shortened by shearing them along the planes *X*—*X* and *Y*—*Y* of Fig. 4 with the result the warp wire ends are cut to the form illustrated in Fig. 5. This operation is preferably performed by a cutting tool or shears such as illustrated and described in my prior Patent No. 2,049,752, dated 50 August 4, 1936.

Referring to Figs. 6, 7 and 8, it will be seen that the warp wire *3* terminates in a steep upwardly inclined end portion *3a*, the wire *2* in a less steeply 55

inclined upwardly directed end portion 2a and the wire 1 in a downwardly inclined end portion 1a.

When the two ends of the fabric to be joined have been prepared as above described, they may be abutted together as shown in Figs. 6 to 9, with the warp wire ends 1a, 2a and 3a of one end of fabric abutted against the corresponding warp wire ends 2b, 1b and 3b, respectively, of the other end of fabric. The end portions 1a and 2b, 2a and 1b, 3a and 3b are then welded together in known manner.

The resulting seam, it will be observed, interrupts the continuity of the twill weave, but if it is desired to maintain the continuity of the twill weave across the seam, the ends of fabric may be abutted together, as shown in Fig. 10, so that warp wire end 1a abuts against warp wire end 3b, warp wire end 2a against warp wire end 2b and warp wire end 3a against warp wire end 1b that is to say, by offsetting one end of fabric with respect to the other end of fabric a distance equal to the pitch of the warp wires.

In forming the seam illustrated in Fig. 10 in which the continuity of the twill weave is maintained across the seam, the wire ends 2a and 2b are bent up at a somewhat more acute angle and may be trimmed off slightly.

It will, of course, be understood that the drawings show the fabric on a greatly enlarged scale and the illustrations are somewhat exaggerated for the sake of clearness. Due to the wire ends being assembled in coplanar relationship while welding, the joint obtained in this manner is perfectly flat and need not be subjected to any difficult rolling or flattening treatment liable to widen the joint and cause marking on the paper when the belt is in use.

Such changes in the method or details as would occur to one skilled in the art are to be considered as coming within the spirit of the invention and the scope of the appended claims.

I claim:

1. The improved method of uniting the ends of twill weave woven wire fabric which consists in removing a plurality of weft wires from the ends of the fabric to be joined, opening out the loose warp wire ends so that every third warp wire end is bent downwardly and every pair of intervening warp wire ends is bent upwardly, severing the warp wire ends shortly beyond where they cross the last remaining weft wire so as to leave downwardly sloping end portions on every third warp wire and upwardly sloping end portions on the intervening warp wires, abutting the ends of the fabric with the warp wires of one end of fabric in line with and abutting the warp wires of the other end of fabric, and finally uniting the abutting warp wire ends by welding, brazing or soldering.

2. The improved method of uniting the ends of twill weave woven wire fabric which consists in preparing each end of fabric by withdrawing the first three end weft wires and removing the next remaining end weft wire by drawing it obliquely to the plane of the fabric while withdrawing it through the end edge of the fabric, so as to progressively raise the end of every third warp wire, thereupon separating the warp ends of every intervening pair of warp wires so as to raise one warp wire end and depress the other warp wire end of each intervening pair of warp wires, subsequently cutting the warp wire ends to leave every third warp wire with a downwardly sloping end portion and the other warp wires

with upwardly sloping end portions, and assembling the ends of fabric so prepared by abutting them with the warp wires of one end of the fabric in line with and abutting the warp wires of the other end of fabric, and finally uniting the abutting warp wires ends by welding, brazing or soldering.

3. The improved method of uniting the ends of twill weave woven wire fabric which consists in removing a plurality of weft wires from the ends of the fabric to be joined, opening out the loose warp wire ends so that every third warp wire end is bent downwardly and every pair of intervening warp wire ends is bent upwardly, shearing across the raised warp wire ends in the plane of the top surface of the fabric and shearing across the depressed warp wire ends in the plane of the under-surface of the fabric to sever the warp wire ends shortly beyond where they cross the last remaining weft wire and thereby to leave downwardly sloping end portions on every third warp wire and upwardly sloping end portions on the intervening warp wires, abutting the ends of the fabric with the warp wires of one end of fabric in line with and abutting the warp wires of the other end of fabric, and finally uniting the abutting warp wire ends by welding, brazing or soldering.

4. The improved method of uniting the ends of twill weave woven wire fabric which consists in preparing each end of the fabric by withdrawing the first three end weft wires and removing the next remaining end weft wire by withdrawing it obliquely to the plane of the fabric while withdrawing it through the end edge of the fabric, so as to progressively raise the end of every third warp wire, thereupon separating the warp ends of every intervening pair of warp wires so as to raise one warp wire end and depress the other warp wire end of each intervening pair of warp wires, subsequently shearing across the raised warp wire ends in the plane of the top surface of the fabric and shearing across the depressed warp wire ends in the plane of the under-surface of the fabric to sever the warp wire ends shortly beyond where they cross the last remaining weft wire end and thereby leaving every third warp wire with a downwardly sloping end portion and the other warp wires with upwardly sloping end portion, and assembling the ends of fabric so prepared by abutting them with the warp wires of one end of fabric in line with and abutting the warp wires of the other end of fabric, and finally uniting the abutting warp wire ends by welding, brazing or soldering.

5. The improved method of uniting the ends of twill weave woven wire fabric which consists in preparing each end of fabric by withdrawing the first three end weft wires and removing the next remaining end weft wire by drawing it obliquely to the plane of the fabric while withdrawing it through the end edge of the fabric, so as to progressively raise the end of every third warp wire, thereupon separating the warp ends of every intervening pair of warp wires so as to raise one warp wire end and depress the other warp wire end of each intervening pair of warp wires, further separating the warp wire ends by further lifting the raised warp wire ends and further depressing the depressed warp wire ends, subsequently shearing across the raised warp wire ends in the plane of the top surface of the fabric and shearing across the depressed warp wire ends in the plane of the under-surface of the fabric to sever the warp wire ends shortly

- beyond where they cross the last remaining weft wire and thereby to leave downwardly sloping end portions on every third warp wire and upwardly sloping end portion on the intervening warp wire, abutting the ends of the fabric with the warp wires of one end of fabric in line with and abutting the warp wires of the other end of fabric, and finally uniting the abutting warp wire ends by welding, brazing or soldering.
- 5 6. The improved method of uniting the ends of twill weave woven wire fabric which consists in removing a plurality of weft wires from the ends of the fabric to be joined, opening out the loose warp wire ends so that every third warp wire end is bent downwardly and every pair of intervening warp wire ends is bent upwardly, severing the warp wire ends shortly beyond where they cross the last remaining weft wire to leave a downwardly sloping end portion on every third warp wire and upwardly sloping end portions on the intervening warp wires, abutting the ends of the fabric with the warp wires of one end of fabric in line with and abutting the warp wires of the other end of fabric, and finally uniting the abutting warp wire ends by welding, brazing or soldering with the two ends of fabric so abutted as to maintain continuity of the twill weave across the seam when the warp wire ends are finally united.
- 10 7. The improved method of uniting the ends of twill weave woven wire fabric which consists in preparing each end of fabric by withdrawing the first three end weft wires and removing the next remaining end weft wire by drawing it obliquely to the plane of the fabric while withdrawing it through the end edge of the fabric, so as to progressively raise the end of every third warp wire, thereupon separating the warp ends of every intervening pair of warp wires so as to raise one warp wire end and depress the other warp wire end of each intervening pair of warp wires, subsequently cutting the warp wire ends overlapped by upwardly sloping warp wire ends and with every third upwardly sloped warp wire end meeting a correspondingly upwardly sloped warp wire end.
- 15 8. The improved method of uniting the ends of twill weave woven wire fabric which consists in preparing each end of fabric by withdrawing the first three end weft wires and removing the next remaining end weft wire by drawing it obliquely to the plane of the fabric while withdrawing it through the end edge of the fabric, so as to progressively raise the end of every third warp wire, thereupon separating the warp ends of every intervening pair of warp wires so as to raise one warp wire end and depress the other warp wire end of each intervening pair of warp wires, subsequently cutting the warp wire ends overlapped by upwardly sloping warp wire ends and with every third upwardly sloped warp wire end meeting a correspondingly upwardly sloped warp wire end.
- 20 9. The improved method of uniting the ends of twill weave woven wire fabric which consists in preparing each end of fabric by withdrawing the first three end weft wires and removing the next remaining end weft wire by drawing it obliquely to the plane of the fabric while withdrawing it through the end edge of the fabric, so as to progressively raise the end of every third warp wire, thereupon separating the warp ends of every intervening pair of warp wires so as to raise one warp wire end and depress the other warp wire end of each intervening pair of warp wires, subsequently cutting the warp wire ends overlapped by upwardly sloping warp wire ends and with every third upwardly sloped warp wire end meeting a correspondingly upwardly sloped warp wire end.
- 25 10. A twill weave woven wire fabric comprising two sections of twill weave wire fabric united together in coplanar relationship by a welded seam, the seam being located between two of the weft wires and formed by welding together the abutting raised ends of every third warp wire and welding together the abutting sloping end portions of each intervening pair of warp wires, the area of the mesh openings being substantially the same at the seam as in the body of the fabric.
- 30 11. A seam for joining two sections of twill weave woven wire fabric, said seam being formed by welding together the abutting raised ends of every third warp wire and welding together the abutting sloping end portions of each intervening pair of warp wires, so as to maintain a continuation of the wave form of the warp wires across the seam.

FERDINAND STEINHART. 60
